UNITED STATES PATENT OFFICE.

JAMES M. LEAVER AND JAMES M. LEAVER, JR., OF OAKLAND, CALIFORNIA.

LUMBER SORTER.

Application filed February 13, 1923. Serial No. 618,858.

To all whom it may concern:

Be it known that we, JAMES M. LEAVER and JAMES M. LEAVER, Jr., citizens of the United States, residing at Oakland, in the county of Alameda and State of California, have invented new and useful Improvements in a Lumber Sorter, of which the following is a specification.

The invention relates to improvements in sorting machinery, especially of a type adapted to sort a mixed delivery of cut lumber in batches of uniform width or length, or both, and has for its particular object the overcoming of much hand labor previously employed in connection with such work, and thereby reducing the cost of sorting and making it feasible to separate, by mechanical means, pieces of lumber into predetermined assortment thereby eliminating much labor at present used to obtain this result.

The object of our invention, as above mentioned, is achieved through the apparatus described hereinafter and illustrated in the accompanying drawings, and the invention consists primarily of a long, horizontal, chain slat conveyor for dragging the miscellaneous pieces of lumber, placed transversely on rails, along the rails over numerous bins, and of rotating selective devices co-operating with the conveyor for tripping the various size boards off of the rails and into the bins. Each bin receiving a certain predetermined size board, though, at the option of operator, the selective devices can be set so as to engage more than one width of board of any predetermined length so as to deposit in one bin two or more widths.

Figure 1 in the drawing is a plan view of a portion of the machine arranged for several separations.

Figure 2 is an end cross section view of Figure 1 and shows the arrangement of lumber supporting rails in relation to the rotating tripping fingers.

Figure 3 is an enlarged sectional drawing of the special supporting rail or "step rail," in operative relation to the rotating tripping fingers, and shows one of the fingers mounted on a disk hub center.

Figure 4 is an equally enlarged plan view of a portion of the step rail showing a finger in the act of striking a board, but in a

slightly different position than would be the case with the finger disks shown in Figures 1 and 3 as will later be explained.

Figure 5 shows an optional gear drive between a pair of tripping shafts, which may be used in place of the chain and sprocket drives indicated in Figure 1.

In further detail it will be seen by reference to Figure 1, a plan view of a lumber sorter having, for illustrative purposes only three steps for length separation of four width separations each, respectively; (in practice the apparatus being extended with its parts multiplied to separate as many lengths and widths as may be predetermined) that a series of bins 1, open on top, has a traveling two strand chain conveyor 2 passing over it. The conveyor is endless and is carried over the sprockets 3, 3 and 4, 4 at the ends of the bin series passing downward and returning in a space beneath the bins (as shown in Figure 2).

The conveyor is what is known in the art as a slat drag conveyor, having slats or cleats 5 spaced to match the bins, and in edge contact with which slats the various pieces of lumber are dragged over the bins while sliding upon supporting rails 6.

At 7 is indicated a chute, down which the mixed lumber is fed to the conveyor. At 8 is a short straight-edge fixed to a platform just preceding the bins, and against which straight-edge an attendant places one end of whatever piece of lumber happens to be handy in the chute, observing at the same time that but one piece lies on the conveyor between two slats, unless the attendant places two or more pieces of the same length and width against the straight-edge and the face of slat, several such pieces of lumber being indicated at 9.

The conveyor is in constant motion, advancing in the direction of the arrow, carrying the pieces of lumber over the bins with their ends resting over the rails 6. One of these rails designated 10 is of step section; as better shown in cross section in Figure 3; and is set in staggered lengths over certain groups of bins for several widths of lumber of a given length.

As the lumber advances, on account of the staggered arrangement of the rail 10, a point will be reached where one end of a piece of lumber will fall from the upper

to the lower step of rail 10 and will then be in a position to be struck by one of the fingers of the revolving selective devices 11, forced off of the lower step of the rail 5 and dropped one end first into the bin beneath, but usually directed by a baffle to proper position in the bin.

The selective devices are carried on shafts 12 arranged in staggered relation like the 10 step rail, and are driven by sprockets 13 through chains 14 from sprockets 15 on a power shaft 16 receiving its power from any convenient source. The shaft 16 is also geared at 17 to the conveyor drive or "head" 15 shaft 18 to actuate the conveyor through the sprockets 3, 3 secured to the shaft.

All other sprockets on the conveyor excepts those mentioned, are on idler shafts, being for support and guidance only.

20 In Figure 2, a cross section of the apparatus, the position of the related elements described is clarified, and in Figure 3 the step rail is shown in enlarged section with the 25 end of a piece of lumber 9' dropped to the lower step 10' of the rail and about to be pushed off by the finger 19 of the selective device or trip 11, to fall into a bin beneath, but whether it will be struck by the finger 19 or not depends on the width of the piece of 30 lumber and the position at which the finger is set on the disk hub 11 keyed to the shaft 12.

The disk and finger operates through a slot 20 in the rail as shown in Figure 3, and the disks are provided with a series of holes 35 21 in order to permit of placing the finger in different positions so as to strike different widths of lumber, each set of disks for a given length of lumber having the fingers arranged to successively push off, first, the 40 widest pieces, then decreasing widths, the last bin of each series having no disk but receiving all narrow width pieces passed by the selective devices preceding. The lower step of the rail 10' is cut away over 45 the last bin in each series, or the rail omitted entirely at those points to permit of the pieces falling.

In practice, since the conveyor travels rapidly, the staggered points of the step rail 50 10 precede somewhat the bin, so as to give the lumber ends time in which to fall to the lower step of the rail before the advance of the striking finger of the selective device.

55 Figure 4 is a plan view showing an optional setting of the selective device, set away from the first edge of the bin a definite distance to insure a definite width of lumber being struck by it. In this arrangement all the fingers of all the devices would be in the same plane and all strike at once, but with the first method described and shown the shock is divided by successive striking, as the fingers are in different rotative relation on the various disks, but all are set the same 60 distance from the bin edges, relying for se-

lective effect on the different time at which they arrive in striking position.

In Figure 5 is shown an optional gear drive connecting a pair of the staggered shafts 12, which may be used in place of the 70 individual chain drives shown in Figure 1 if desired.

As will readily be seen from a study of this specification, this apparatus is one capable of wide modifications and may be used 75 for the separation of material other than lumber, where automatic separation of lengths and widths is desired, without departing from the spirit of the invention, and we therefore feel entitled to the following 80 claims.

We claim:—

1. In a lumber sorter, a series of bins, an endless traveling conveyor arranged to convey lumber across the top of the bins, said conveyor passing over the bins, around the ends and returning under the bins, and a plurality of selective tripping devices spaced over the bins along the conveyor operatively geared thereto in positive relation to a plurality of definite points on said conveyor and adapted to trip lumber therefrom to the bins. 90

2. In a sorting apparatus, a plurality of supporting rails, a power actuated drag conveyor adapted to drag miscellaneous size 95 shapes along said rails, spaced tripping devices arranged along said conveyor and operatively connected with said conveyor for positive action therewith and adapted to trip said shapes from said rails, the devices being 100 variously positioned and timed in relation to definite points on the conveyor to act selectively on said shapes.

3. In a lumber sorter, a traveling lumber conveyor embracing a plurality of conveyor 105 chains, transversely disposed spaced cleats connected to said chains for travel therewith, selective devices spaced along and operatively connected to the conveyor and respectively timed to operate at various definite distances from the advance edges of said cleats. 110

4. In a sorting apparatus, a series of bins, a traveling conveyor arranged above and passing over said bins adapted to convey 115 miscellaneous size shapes thereover, and a plurality of selective tripping devices over said bins spaced along said conveyor operatively connected therewith for positive action in relation to a plurality of definite points on said conveyor and adapted to trip 120 selectively, substantially similar shapes from said conveyor, respectively, to said bins.

5. In a sorting apparatus, a series of bins, a power actuated traveling conveyor arranged over said bins adapted to convey 125 miscellaneous size pieces of lumber across said bins, and a plurality of selective tripping devices over said bins spaced along said conveyor operatively connected there- 130

with for positive action in relation to a plurality of definite points on said conveyor and operative against an end of the lumber pieces for tripping them from the conveyor to the 5 bins.

6. In a lumber sorter of the character described, a traveling conveyor adapted to convey miscellaneous size pieces of lumber transversely arranged thereon, a plurality of 10 tripping devices spaced along said conveyor and operatively connected for positive action therewith in relation to a plurality of definite points on said conveyor, said tripping devices being variously positioned laterally with respect to the conveyor and said 15 points to respectively trip from the conveyor pieces of substantially similar length.

7. In a lumber sorter of the character described, a traveling conveyor adapted to convey 20 miscellaneous size pieces of lumber transversely arranged thereon, a plurality of tripping devices spaced along said conveyor and operatively connected for positive action therewith in relation to a plurality of definite points on said conveyor, said tripping devices being variously positioned with respect to said points to respectively trip from said conveyor pieces of substantially similar width.

8. In a lumber sorter of the class described, a traveling conveyor adapted to convey miscellaneous size pieces of lumber transversely arranged thereon, a plurality of 25 tripping devices spaced along said conveyor and operatively connected for positive action therewith in relation to a plurality of definite points on said conveyor, said tripping devices being variously positioned laterally and longitudinally of the conveyor 30 with respect to said points to respectively trip from said conveyor pieces of substantially similar length and width.

9. In a lumber sorter, a plurality of rails, a stepped rail arranged in staggered lengths, 45 a traveling conveyor adapted to convey various size pieces of cut lumber along said rails while lying transversely thereon and successively drop an end of various length pieces to the lower step of said stepped rail, rotating trips spaced along said stepped rail operatively connected with the conveyor and adapted to strike the end of a piece of lumber riding on the lower step of the rail and drop it from the conveyor.

10. In a lumber sorter, a traveling conveyor adapted to convey miscellaneous size pieces of cut lumber, a feeding guide for aligning one end each of different size pieces, 50 tripping devices spaced along the conveyor operatively connected therewith and adapted to operate against the misaligned ends of said pieces.

11. In a lumber sorter, a series of horizontally disposed bins, an endless traveling conveyor supported on top of said bins, passing 55

over the bins, around the ends and returning under the bins, said conveyor being adapted to convey miscellaneous size pieces of cut lumber over said bins, selective tripping devices over some of the bins operatively connected with said conveyor for positive action therewith and adapted, each respectively, to release one end each, respectively, of a predetermined size piece of lumber from said conveyor and precipitate it released end first into a bin. 70

12. In a lumber sorter, a traveling conveyor adapted to convey various length and width pieces of cut lumber transversely arranged thereon, a plurality of selective tripping devices along said conveyor operatively connected thereto for positive action therewith in relation to a plurality of definite points thereon, said tripping devices being variously positioned laterally and longitudinally of the conveyor and operatively variously timed in relation to said definite points adapted to trip successively from the conveyor in spaced positions, pieces of lumber of successively increasing length in 80 batches of successively decreasing widths. 85

13. In a lumber sorter, supporting rails, means for moving miscellaneous size pieces of lumber along said rails whilst supported transversely thereon, selective devices spaced along the line of travel adapted to strike some of said pieces of lumber and move them transversely of the rails and throw one end from a supporting rail. 95

14. In a lumber sorter, a series of laterally arranged bins, an endless traveling lumber conveyor operatively arranged to pass over the top of the bins, around the ends, and return under the bins. 100

15. In a lumber sorter, a traveling lumber conveyor, a plurality of selective tripping devices spaced along the conveyor operatively geared thereto for positive action therewith in relation to a plurality of definite points on said conveyor and adapted to trip lumber from the conveyor. 105

16. In a lumber sorter of the class described embracing a traveling lumber conveyor, a selective tripping device operatively geared for positive action with the conveyor 115 in relation to a plurality of definite points thereon embracing a revolvable striker adapted to strike the end of a piece of lumber placed on the conveyor in relation to one of said definite points. 120

17. In a lumber sorter of the class described, a selective tripping device embracing a revolvable disk, a lumber striking finger thereon adapted for setting in various circumferential positions around said disk. 125

18. In a sorter for cut lumber, a plurality of supporting rails embracing upper and lower rails, a conveyor for moving various size pieces of lumber along said rails, some of said upper rails being arranged to drop 130

- an end of certain length pieces of lumber to a lower rail, and means co-operating with the conveyor for pushing the pieces endwise from the lower rail.
5. 19. In a lumber sorter of the class described, a lumber conveyor having spaced strands of conveying elements, means associated with the conveyor for tripping lumber therefrom and dropping it therefrom between said strands.
10. 20. In a lumber sorter of the class de-

scribed, lumber supporting tracks, a drag conveyor comprising spaced strands of chain with transverse slats connecting same arranged to drag lumber along said tracks 15 laid transversely thereon, tripping means geared for positive action with the conveyor arranged to trip lumber from the conveyor dropping it therefrom between said strands of chain.
